UNITED STATES PATENT OFFICE

149,286

DESIGN FOR A DRESS

Rose Malluk, Cliffside Park, N. J.

Application July 16, 1947, Serial No. 140,316

Term of patent 3½ years

(Cl. D3—26)

To all whom it may concern:

Be it known that I, Rose Malluk, a citizen of the United States of America, residing in Cliffside Park, county of Bergen, and State of New Jersey, have invented a new, original, and ornamental Design for a Dress, of which the following is a specification, reference being had to the accompanying drawing, forming part thereof.

Fig. 1 is a front view of a dress, showing my new design.

Fig. 2 is a rear view thereof.

I claim:

The ornamental design for a dress, substantially as shown.

ROSE MALLUK.
